UNITED STATES PATENT OFFICE.

JOHN H. GLOVER, OF OSHKOSH, WISCONSIN, ASSIGNOR OF ONE-HALF TO
ROBERT McMILLEN, OF SAME PLACE.

SASH AND DOOR STICKER.

SPECIFICATION forming part of Letters Patent No. 310,579, dated January 13, 1885.

Application filed August 12, 1884. (No model.)

To all whom it may concern:

Be it known that I, JOHN H. GLOVER, a citizen of the United States, residing at Oshkosh, in the county of Winnebago and State 5 of Wisconsin, have invented certain new and useful Improvements in Sash and Door Stickers; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 My invention relates to improvements in sash and door stickers. This class of machines as heretofore constructed are adapted to operate upon but one edge of the stuff or material at a time, and it has therefore been necessary, when desirous to groove or mold both 20 edges of the stuff, to turn every piece and run it through the machine a second time.

The object of my improvement is to provide 25 a machine which will produce the desired work upon both edges of the stuff simultaneously, whereby one person is enabled to do more than double the amount of work in a given time that could be done upon the ordinary sticker.

30 My invention and a sample of the work performed thereby are shown and further explained by reference to the accompanying drawings, in which—

Figure 1 represents a front side view. Fig. 35 2 is a top view. Fig. 3 is an end view. Fig. 4 is a detail. Fig. 5 represents a sample of the work performed by my machine upon the edges of the stuff in passing once through it.

Like parts are represented by the same reference-letters throughout the several views.

40 A is the frame of the machine.

B is the adjustable table by which the stuff is supported when passed between the cutting-heads C and D.

45 E is the table-adjusting screw by which the table is raised, lowered, and adjusted to conform to the width of the stuff acted upon. Both of the cutter-heads C and D are detachably connected to their shafts F and G in the 50 ordinary manner, and may be removed and substituted by such others as may be required

to do the various kinds of work pertaining to sash and doors. Motion is communicated to the cutter-heads C and D from the motive power of the machine through band H, band-pulley I, shaft J, band-pulleys K and L, and bands M and N, and shafts F and G. 55

O O are corrugated feed-rolls, by which the stuff is fed forward between the cutting-heads. Motion is communicated to the feed-rolls O O 60 from the shaft J by pulley Q, band R, pulley S, shaft T, pulley U, band V, pulley W, pinion A', pinions B' and C', and shafts D' and E'.

To accommodate my sticker to the various widths of material when operating two cutter-heads simultaneously, it becomes necessary to provide for the vertical adjustment of the lower cutter-head, D, with the supporting-table, and when desirous to operate upon one side of the stuff only it becomes necessary to provide for 70 the vertical adjustment of the lower cutter-head, D, independently of the supporting-table, whereby it may be brought below the upper surface of the table, so that the material may pass over it without contact therewith. The 75 vertical adjustment of the lower cutter-head, D, is accomplished by means of screw F'.

G' is a guide by which the upper edge of the stuff is held in place as it passes between the cutting-heads. The upper end of the guide 80 G' operates in and is held in place by the bracket or ways H', and is raised and lowered by the adjusting-screw I', which screw I' moves upward and downward in a screw-cut thread in said bracket H' as it is turned, and carries 85 with it said guide G', which guide is attached to the lower end of the screw by collars in the ordinary way. The lower edge of the material is held in place by the guide J', which guide J' is horizontally adjusted, corresponding 90 to the different thicknesses of the stuff, by the hand-screws K' K'. The outer end of the hand-screws K' K' are loosely affixed in brackets L', in which they are adapted to turn, and are provided with collars operating upon the 95 respective sides of said brackets, which prevent the screws from moving laterally in the brackets as the guide J' is adjusted. The inner projecting ends of the screws K' operate in the lugs M', which are provided with screw-threaded openings for the reception of said screws, whereby said guide may be adjusted 100.

horizontally toward the right and left, as desired, by turning said hand-screw K'. The upper guide, G', is horizontally adjusted to conform to the lower guide, J', by loosening 5 the nuts on screw N', the retaining-plate of said upper guide being provided with slots which permit of the required adjustment, as shown in Fig. 2. The guides J' and G' are adapted, when moving the edge of a board 10 like that shown in Fig. 5, to enter the grooves formed by the respective cutter-heads and guide the stuff as it moves between and is operated upon by them.

The shaft G, to which the movable cutter-head D is attached, has its journal-boxes A" 15 affixed to the slide d, operating in the movable yoke B'', which yoke is supported by the adjusting-screw F' and held in place in connection with the stationary frame A, as shown 20 in Fig. 4, by the angular blocks C'' C', which blocks engage in the conversely-shaped angular retaining-ways D'' D'', formed upon the edge of the vertical end pieces, E'' E', of said frame A. Both screws E and F' are supported 25 at their lower ends in sockets a a, in which they are free to turn when adjusting the table or cutter-head.

The yoke B'', to which the cutter-head D is attached, is provided with a screw-cut bracket, 30 F'', in which the screw F' operates, causing said yoke and cutter-head D to move upward or downward, as may be required. The screw E operates in a screw-cut hole in the lug b, which projects from the rear side of the table B, and said table is raised or lowered by the action of the screw E as it is turned, and thus adjusted to the different widths of material. The journal-boxes A" A'', which support 35 the lower cutter-head, D, and its shaft, are connected to the yoke B by a dovetail slide, d, one end of which is shown in Fig. 1, which slide operates in a horizontally-arranged dovetail groove, g, one end of which is also shown in said Fig. 1. The inward-projecting end of 40 the hand-screw N turns at a fixed point in the arm R' of yoke B'', through which arm the screw N passes, and is provided with collars, by which it is prevented from moving laterally as it is turned, while the arm d' moves 45 forward and rearward upon the screw N, carrying with it the journal-boxes A'', shaft G, and cutter-head D. Thus it is obvious that by turning the hand-screw N the cutting-head D is adjusted to the various thicknesses of 50 material. As the shaft G, with its driving-pulley h, is raised and lowered in the act of adjusting the cutter-head D, it becomes necessary to tighten or loosen the belt N, which end is accomplished by the band-tightening 55 pulley H'' and lever I''. The lever I is pivoted at its lower end to the bracket J'' by bolt K'', which bracket is affixed to the frame A. The pulley H'' is secured to the side of the lever I'' by bolt L''. As the handle or lever is 60 drawn forward the pulley H'' is caused to press against the band N, whereby said band is retained at its required tension. The band-

pulley S is adapted to turn either with or independently of the shaft T. When desirous to stop the feed-rolls the pulley S is moved inward away from and out of contact with the clutch M'', when it rotates freely upon the shaft. The clutch M'' is rigidly affixed to the shaft and rotates with it.

To the side of the pulley S is affixed a clutch, 75 N''. When the pulley S is moved outward toward the clutch M'' the two clutches engage with each other, thereby causing the pulley S to rotate. The clutch N'' is operated by the lever O'', which lever is pivoted to a bracket, 80 P'', upon the side of the frame A. The upper cutter-head, C, is horizontally adjusted by means of the hand-screw A'', which has bearings upon the respective sides of the frame A in a loosely-fitting hole. The upper cutter-head, C, with its shaft F and journal-boxes a' 85 a', is supported upon the movable yoke B'', which yoke, shaft, cutter-head, and boxes are all moved forward or rearward, as may be required for the proper adjustment of the cutter-head, by turning said screw A''. The screw A'' operates in a screw-cut hole in a downward-projecting lug of said yoke B''. The journal-boxes a' are retained in place upon the yoke B'' by the upward-projecting lugs g' g' and the bolts 90 h' h', which bolts h' h' pass down through the boxes and the yoke B''.

Having thus described my invention, what I claim as new, and desire to secure by Letters Patent, is—

1. In that class of sash and door stickers having an upper and lower cutting-head adapted to simultaneously groove both edges of the stuff, the combination of the stationary bracket or ways H', adjusting-screw I', and 105 guide G', said guide being adjusted by said screw to enter the groove formed by the upper cutter-head, horizontal adjusting-screws K' K', brackets L', lugs M', and guide J', said guide J' being adjusted by said screws K' K' 110 to enter the groove formed by the lower cutting-head, as set forth.

2. In that class of sash and door stickers having an upper and a lower cutting-head, the device for producing the vertical adjustment of the table and lower cutting-head, consisting in the combination, with the frame A, having seat a, of the adjusting-screw E, supported in said seat, vertically-adjustable table B, yoke B'', movable vertically on ways D'' D', 120 and ways D'' D'', substantially as and for the purpose specified.

3. In that class of sash and door stickers having an upper and a lower cutting-head, the device for producing the horizontal adjustment of the lower cutting-head, consisting in the combination, with the vertically-moving yoke B'' and retaining-ways D'', of the slide d, supported in horizontally-arranged ways in said yoke B'', journal-boxes A" A'', affixed to 125 said slide d, shaft G, and lower cutting-head, D, substantially as and for the purpose specified.

4. The combination, with the stationary

frame A, upper cutting-head, C, mounted upon a shaft operating in fixed journal-boxes upon said frame, table B, adjustable vertically relatively to said frame by screw E, to support the lower edge of the stuff, rigidly-affixed bracket H', adjusting-screw I', and guide G', adjustable by said screw I', to hold the upper edge of the stuff, lower cutting-head, D, supporting-shaft G, journal-boxes A" A", horizontally-moving slide d, and vertically-moving yoke B", operating in vertical ways D", said slide d and yoke B" serving to produce the

required horizontal and vertical adjustment of said lower cutting-head to conform to the thickness and width of the stuff, whereby both edges of the stuff may be simultaneously operated upon, all substantially as and for the purpose set forth. 15

In testimony whereof I affix my signature in presence of two witnesses.
